UNITED STATES PATENT OFFICE

ROBERT A. STEVENSON, OF LANCASTER, OHIO

DESIGN FOR AN AUTO JUG

Application filed August 12, 1931. Serial No. 40,832. Term of patent 14 years.

To all whom it may concern:

Be it known that I, ROBERT A. STEVENSON, a citizen of the United States, residing at Lancaster, in the county of Fairfield and State of Ohio, have invented a new, original, and ornamental Design for an Auto Jug, of which the following is a specification, reference being had to the accompanying drawings, forming part thereof.

Figure 1 is a front view of an auto jug, showing my new design;

Figure 2 is a side view of the upper portion of the jug; and

Figure 3 is a top view.

I claim:

The ornamental design for an auto jug, as shown.

ROBERT A. STEVENSON.
